PACKING MEANS FOR HYDRAULIC JACKS

Homer R. Rosenberry, Euclid, and Ray P. Rosenberry, Cleveland, Ohio, assignors to Carl W. Brand, Cleveland, Ohio

Application January 6, 1932, Serial No. 585,004
Renewed July 7, 1936

4 Claims. (Cl. 286—26)

This invention relates to packing means for hydraulic jacks, and the like, and the principal object of the invention is to provide new and improved packing means of this character.

5 In the drawing accompanying this specification and forming a part of this application, we have shown, for the purpose of illustration, forms which our invention may assume, and in this drawing:

10 Figure 1 is a vertical longitudinal sectional view of an embodiment of the invention.

Figure 2 is a similar view of another embodiment of the invention, while

15 Figure 3 is an enlarged fragmentary vertical sectional view of the upper end of the ram cylinder shown in Figure 2.

20 Referring to Figure 1 of the drawing, the invention is disclosed in connection with a hydraulic jack comprising a base 90 having a vertically extending substantially cylindrical wall 91 cast integrally therewith, which defines a reservoir 92 and which is provided with a handle 93 cast integrally therewith. The upper portion of the wall 91 is internally screw threaded to receive a correspondingly threaded closure 94 which effectively seals the upper portion of the reservoir 92 and which is provided with an annular recess 95 in its lower surface forming a shoulder 96.

25 30 Also, cast integrally with the base 90 is a centrally disposed vertically extending annular boss 97 which is internally screw threaded to receive the correspondingly threaded lower portion of a ram cylinder 98. The upper end of the cylinder 98 is provided with a reduced portion 99 for telescopic engagement within the recess 95, the shoulder 96 of which prevents any lateral displacement of the cylinder 98 and maintains the same in axial alignment.

35 40 Mounted for vertical movement in the ram cylinder 98 is a ram 100 provided with a piston 101 at its lower end. The piston 101 embodies a packing member 102 of cup-shaped formation, which is clamped against the lower end of the ram 100 by a screw 103. The screw 103 is provided with an annular recess 104 which is adapted to receive the depending flange 105 of the packing member 102, the latter being provided with a beveled lower edge 106 which insures a very accurate contact with the walls of the ram cylinder 98 when fluid pressure is applied.

45 50 The screw 103 is also provided with a centrally disposed recess 107 in its lower end which communicates with the recess 104 through ports 108, so that when fluid is forced into the lower end of

the ram cylinder it will enter the space between the flange 105 of the packing 102 and force the packing into intimate contact with the ram cylinder 98 when the ram is elevated.

5 10 The upper end of the ram 100 extends through a centrally disposed aperture 109 provided in the closure member 94, leakage of fluid at this point being prevented by means of a leather packing member 110 which is substantially of inverted L-shape in cross-section and disposed within an internally screw threaded recess 111 formed in the closure 94. This recess is provided with an annular outwardly and downwardly inclined shoulder 112 for seating engagement with the horizontal flange 113 of the packing member 110. 15 A washer 114 is threaded into the upper end of the recess 111 and is adapted to not only compress the packing member 110 into sealing engagement with the ram 100 but also to provide an upper bearing surface for the ram which is spaced from the lower bearing surface provided by walls of the aperture 109 in the closure 94. The lower edge of the vertical flange 115 of the packing member 110 is beveled as indicated at 20 25 116 so as to provide an annular opening 117 adapted to receive fluid leaking through the aperture 109, the pressure of which fluid maintains the flange 115 in sealing engagement with the ram during the elevation thereof.

30 By means of this construction a very rigid and durable structure is obtained, in that the ram is provided with a two-point bearing surface adjacent its upper end, having a packing disposed therebetween, and the ram is also provided with a bearing surface at its lower extremity afforded 35 by the screw 103 which functions as a pilot during the elevation of the ram, and maintains the ram laterally braced in axial alignment independently of the packing 102, and notwithstanding any wear to this member.

40 45 The upper portion of the ram 100 carries a jack-screw 118 which is threaded into an internally screw threaded sleeve 119 disposed within an axial bore 120 for seating engagement with an annular shoulder 121 formed therein and which is maintained against rotation by means of a locking screw 122. The upper portion of the jack-screw 118 is provided with the usual saddle portion 123 for engagement with the object being raised.

50 55 Fluid under pressure is supplied to the ram cylinder 98 beneath the piston 101 by means of a pump (not shown).

The escape of fluid from the ram cylinder 98 is controlled by means of a needle valve 124, the

inner end of which fits the outer end of a passage 125 formed in the boss 97 for establishing communication between the interior of the ram cylinder 98 and the reservoir 92 when the valve 124 is unseated. The outer end of the valve 124 extends through a packing 126 and is threaded into a plug 127 which is in turn threaded into a boss 128 formed on the wall 91 of the reservoir 92. The outer extremity of the valve 124 is provided with a pin 129 adapted to be engaged by a bayonet joint slot provided in a suitable operating handle.

In Figures 2 and 3 there is shown another embodiment of the invention which is substantially the same as that shown and described in Patent 1,876,023, granted to R. P. Rosenberry, September 6, 1932, and therefore need not be described in detail. In this particular form of the invention, a reservoir 130 and ram cylinder 131 are cast integrally with one another in side-by-side relation. A ram 132 is mounted for vertical reciprocation within the cylinder 131 and is provided at its upper end with the usual saddle 133. The ram 132 is disposed in spaced relation with the walls of the cylinder 131 throughout its length and is urged upwardly by displacement when fluid is forced into the cylinder 131. A needle valve 134 controls communication between the cylinder 131 and the reservoir 130 through a port 135, which valve is closed when the ram is elevated and is opened to permit fluid to escape back to the reservoir 130 from the ram cylinder when it is opened, thus permitting the ram 132 to be lowered.

According to the present invention the upper end of the ram cylinder 131 is provided with an internally screw threaded recess 136 formed at its lower end with upper and lower shoulders 137 and 138 respectively. A washer 139 surrounds the ram 132 in seating engagement with the lower shoulder 138 and provides a lower bearing surface for the ram 132. Disposed above the washer 139 and also surrounding the ram 132 is a leather packing member 140 having a vertical flange 141 which is beveled at its lower edge as indicated at 142 to provide an annular passage 143 above the washer 139, and a horizontal flange 144 which is disposed in seating engagement with the upper shoulder 137.

The packing member 140 is maintained in position and in sealing engagement with the ram 132 by means of a washer 145 which is threaded into the recess 136, and the inner edge of which is beveled to provide an annular passage 146 surrounding the ram 132. The washer 145 is also provided with a plurality of radially extending grooves 147 for registry with an overflow passage 148 formed in the side of the recess 136 for establishing communication between the recess 136 and the upper portion of the reservoir 130. Seated upon the upper face of the washer 145 is a second washer 149 which is disposed in spaced relation with the ram 132 and which provides a seat for a second leather packing member 150 having a vertically extending flange 151 and a horizontally extending flange 152. The vertical flange 151 extends downwardly between the washer 145 and the ram 132 and is beveled at its lower end as indicated at 153 to provide an annular duct 154. The horizontal flange 152 is maintained in seating engagement with the upper face of the washer 149 and in sealing engagement with the ram 132 by means of a third washer 155 which is also threaded into the recess 136, and which is provided with transversely extend-

ing grooves 156 adapted to be engaged by a suitable tool, such as a spanner or the like.

By means of this construction, a three-point bearing of substantial length is provided for the ram, thereby insuring that the ram is maintained against tilting, notwithstanding the absence of lateral support at its lower end, such as is ordinarily provided by a piston. Also, the flanged packing members 140 and 150 provide a very effective seal for the upper portion of the ram in that they are of flexible leather and quickly respond to any internal pressure so as to intimately engage the ram and effectively prevent leakage. The lower packing member 140 forms a main packing member, while the upper packing member 150 functions as a wiper for preventing the escape of any fluid which might leak past the lower member 140. Any fluid passing the member 140 is collected in the groove 146 and returned to the reservoir through the port 148, thus resulting in a practically leak proof construction. Before the jack is initially operated, the pressure within the jack is equal to that of atmosphere. Upon the first upward movement of the ram, air from the outer atmosphere is drawn past the packing member 150 and into the upper portion of the reservoir 130. Of course, there is no leakage of fluid under these conditions. When the ram 132 is lowered by operating the valve 134, this air is compressed in the reservoir 130 and exerts pressure on the upper packing member 150, which is sufficient to force the same into sealing contact with the ram 132 and prevent leakage during this operation. Thus, the present jack construction eliminates one of the objectionable features common in prior jacks, namely, leakage when the jack is lowered, and results in a mechanism the exterior of which is at all times free from oil and the dirt accumulated thereby.

It will be understood by those skilled in the art that the embodiment herein disclosed accomplishes at least the principal object of the invention, that it has uses and advantages other than those herein particularly referred to, and that various changes and modifications may be made without departing from the spirit of the invention, and accordingly, the embodiment herein disclosed is illustrative only, and our invention is not limited thereto.

We claim:

1. Packing means for relatively movable members, wherein the first of said members extends into the second member, the second member having a bore and a threaded counter-bore, through which said first member reciprocates, the defining wall of said bore being spaced a predetermined distance from said first member, and the defining wall of said counter-bore being spaced a greater distance from said first member; said bore being separated from said counter-bore by an annular shoulder, the supporting surface of which is inclined from the edge of said shoulder away from said first member and from said counter-bore; a packing member having a portion disposed in said bore and provided with a beveled surface inclined in a direction opposed to the direction of inclination of the supporting surface of said shoulder, and having an integral portion seated upon said shoulder, formed to conform to said inclined supporting surface; and a securing member threaded into said counter-bore for securing said packing member in position, and operating to compress the packing member between itself and the edge of said shoulder.

2. Packing means for relatively movable members, wherein the first of said members is elongated and extends into the second member, the second member having a bore and a threaded counter-bore, through which said first member reciprocates, the defining wall of said bore being spaced a predetermined distance from said first member, and the defining wall of said counter-bore being spaced a greater distance from said first member; said bore being separated from said counter-bore by an annular shoulder, the supporting surface of which is inclined from the edge of said shoulder away from said first member and from said counter-bore; a packing member having a portion disposed in said bore and provided with a beveled surface inclined in a direction opposed to the direction of inclination of the supporting surface of said shoulder, and having an integral portion seated upon said shoulder, formed to conform to said inclined supporting surface; a securing member threaded into said counter-bore for securing said packing member in position, and operating to compress the packing member between itself and the edge of said shoulder; a ring of a diameter similar to the diameter of said shoulder, disposed in said counterbore, resting upon said securing member and having a supporting surface disposed substantially at right angles to the longitudinal axis of said first member; a packing member having a beveled portion disposed between said first member and said ring and having an integral portion seated upon the supporting surface of said ring; and a second securing member threaded into said counter-bore and having an inclined surface for clamping said

packing member between itself and the outer corner of said ring.

3. Packing means for relatively movable members, wherein the first of said members extends into the second member, the second member having a bore and a counterbore through which said first member extends, said bore and counterbore being separated by an annular shoulder, the surface of which is inclined away from said counterbore; packing means disposed in said counterbore and bearing on said shoulder; and clamping means secured in said counterbore and operating to compress said packing means between itself and the edge of said shoulder.

4. Packing for longitudinally extending relatively movable means, comprising: packing material; and longitudinally spaced clamping means interposed between said movable means, fixed with respect to a first of said movable means, and having spaced surfaces extending at converging angles toward the longitudinal axis of the other of said movable means, one of said surfaces terminating short of said other movable means, and said surfaces being operable to clamp said packing material between said shortened terminal and the other of said surfaces; said packing material having an extension disposed between said shortened terminal and the other of said movable means, and said extension being provided with a beveled edge inclined from a point adjacent said other movable means in a direction toward said shortened terminal portion.
